UNITED STATES PATENT OFFICE.

SAMUEL HUBER, OF DANVILLE, PENNSYLVANIA.

IMPROVEMENT IN RAILWAY-RAIL CHAIRS.

Specification forming part of Letters Patent No. 141,275, dated July 29, 1873; application filed June 28, 1873.

To all whom it may concern:

Be it known that I, SAMUEL HUBER, of Danville, in the county of Montour and State of Pennsylvania, have invented a new and useful Improvement in Rail-Joints, of which the following is a specification:

The main object of this invention is to prevent the ends of the rails of railroad tracks from being battered or damaged by passing trains; and it consists of a cavity or recess beneath the joint of the rails, whereby a certain degree of elasticity is allowed the ends of the rails.

In the drawing, Figure 1 represents a side view. Fig. 2 is a sectional top view of the chair, and Fig. 3 is a vertical cross-section of Fig. 1 taken on the line *x x*.

Similar letters of reference indicate corresponding parts.

A is the chair; B, the rails. D represents the joint of the rails. D is the bed upon which the rails rest. E is the cavity made in this bed beneath the joint, between the bearing-surfaces F F.

The chair may be made in any manner so that the cavity E is secured. It may be made in two or more pieces, either of cast or wrought iron or steel. In this example of my inven-

tion I make the chair in two pieces and fasten the parts together with one or more spikes or bolts. The form of the chair is seen in the cross-section, Fig. 3.

G is a fastening bolt or spike.

The chair is cut away in the parts which hold the bed-flanges of the rail, as represented at H in the drawing, which leaves additional strength at the ends of the chair to support the bearing-surfaces at F F, as seen at I.

The rails of a railway always fail at the ends first; the ends being supported on a solid bearing, there is no elasticity, and the continual pounding of the wheels batters and "brooms" up the ends, and soon renders the rail unfit for service unless repaired. By allowing the ends to give in a slight degree their battering is prevented and the rails are preserved.

Having thus described my invention, I claim as new and desire to secure by Letters Patent—

A rail-chair having a cavity or recess, substantially as seen at E, as and for the purposes described.

SAMUEL HUBER.
